Patented Oct. 21, 1969

215,668

COMBINATION TOOL FOR GOLFERS

Jon Hedu, Watertown, Conn., assignor to The W. E. Bassett Company, Derby, Conn., a corporation of Connecticut

Filed Apr. 16, 1969, Ser. No. 16,759

Term of patent 14 years

Int. Cl. D22—03, 99; D8—02
U.S. Cl. D34—5

FIG. 1 is a view in perspective, from above and from the side, showing the combination tool of my design;
FIG. 2 is a front elevation of the combined tool;
FIG. 3 is a side view of FIG. 2;
FIG. 4 is a top-end view of the tool in FIG. 2; and
FIG. 5 is a lower-end view of the tool in FIG. 2.

I claim:

The ornamental design for a combination tool for golfers, substantially as shown.
